UNITED STATES PATENT OFFICE.

McCLINTOCK YOUNG, OF FREDERICK, MARYLAND.

ART OF AND MACHINE FOR MAKING BOXES, &c.

SPECIFICATION forming part of Letters Patent No. 397,162, dated February 5, 1889.

Application filed August 30, 1886. Serial No. 212,210. (No model.)

To all whom it may concern:

Be it known that I, MCCLINTOCK YOUNG, of Frederick, in the county of Frederick and State of Maryland, have invented certain new and useful Improvements in the Art of and Machines for Making Boxes of Paper, &c., of which the following is a specification.

My invention relates to improvements in the manufacture of that class of boxes which are produced from strips of paper or its equivalent—such, for instance, as combined paper and cloth, &c.; and my object mainly is to produce from a strip of paper, &c., a series of connected longitudinally pasted and flattened box-tubes which upon being separated from each other and expanded or opened are converted into boxes.

My invention, hereinafter particularly pointed out by the claims, consists in certain novel methods and in improvements in mechanism employed for carrying out such methods.

The accompanying drawings show a suitable organization of mechanism and some modifications thereof for carrying out my invention.

Some of my improvements may be used without others or in connection with equivalents for omitted features.

Figure 1 is a plan view of the machine. Fig. 2 is a side elevation thereof. Fig. 3 is a plan view with various parts omitted, the bed-plate and the reciprocating frame which carries the cutters, printing-stamp, &c., being among the omitted parts. Fig. 4 is a side elevation with parts omitted. Fig. 5 is a view partly in plan and partly in section on the line 5 of Fig. 4. Fig. 6 is a view partly in end elevation and partly in section on the line 6 of Fig. 4. Fig. 7 is a view partly in end elevation and partly in section on the line 7 of Fig. 2. Fig. 8 is a view partly in end elevation and partly in section on the line 8 of Fig. 4. Fig. 9 is a view partly in end elevation and partly in section on the line 9 of Fig. 4. Fig. 10 is an elevation of the cross-head slide of the reciprocating frame which carries the cutters, &c. Fig. 11 is an inverted plan or bottom view of the reciprocating frame detached from its cross-head slide, with the cutters, &c., carried thereby;

and Fig. 12 is a similar view of a portion of the reciprocating frame of a construction adapted to a modification of the printing apparatus by duplicating it. Fig. 13 is a plan 55 of the reciprocating carrier for the feeding-clamp. Fig. 14 is a sectional view on the line 14 of Fig. 6 of the head of the feeding-clamp. Fig. 15 is a view partly in elevation and partly in section on the line 15 of Fig. 7, showing the former and supporting-plate for the paper while being pasted, folded, and pressed, and means for pressing the pasted tube; and Fig. 16, a plan of the supporting-plate and former detached. Fig. 17 is a plan of one of 65 the folding-plates detached, and Fig. 18 a plan of the vibrating lever and support for the folding-plate. Figs. 19 and 20 show an inverted plan or bottom view and a side elevation of the cutters and creasers and their 70 head or frame, and Figs. 21 and 22 are similar views of a modification thereof. Fig. 23 is a diagrammatic view designed to represent the manner in which the paper is printed, cut, creased, and folded into connected flattened 75 box-tubes. Fig. 24 is a view in perspective of one of the boxes open at one end. Fig. 25 is a view of the same character as Fig. 23, showing a modification of the box-tubes; and Fig. 26, a view in perspective of a box produced from one of such modified tubes. 80

A strip of paper or its equivalent, *a*, is supplied from a roll, *A*, and is advanced intermittently or step by step, by means such as in turn to be described, a distance at each 85 feeding actuation equaling the length of a box-tube blank minus the combined length of the two end flaps or securing-lips thereof, when they are provided. When, however, certain features are omitted and box-tubes 90 formed for open-ended boxes, as hereinafter to be explained, the length of feed of the strip at each actuation, while remaining the same, is such as to advance it the length of a box-tube blank. The roll *A*, about which the 95 paper is wound, is mounted to rotate on a stud-shaft, *a'*, supported by a bracket, *A'*, secured to the base or bed-plate *A*² of a suitable main frame at one end thereof. Too free rotation of the roll and unwinding of the paper 100 therefrom is prevented in suitable way. As shown, a rubber collar, *A*³, is loosely sleeved

upon the shaft a' and embraces the projecting hub a^2 (see dotted lines, Fig. 1) of the roll, and this collar is compressed endwise and held by the metal collar or washer a^3 and a 5 set-screw in obvious way, so as to produce sufficient friction against the roll to prevent it from turning too readily, thus requiring that proper tension be exerted upon the strip to unwind it. The strip passes first over a 10 roller between guides a^4 a^4 and to suitable printing apparatus, by which desired words or marks may be printed upon it during cessations in its feeding movement through the machine, the printing being done in lines such 15 as to appear upon any desired surface or upon all sides of a box when completed, as preferred. In this instance the strip is printed upon in such manner that the four sides of the box will be marked. The printing-stamp, 20 as well as cutters, creasers, and primary folders, farther on to be described, are carried by a vertically-reciprocating frame or plate, A^4 , to and beneath which they are secured. A driving-shaft, B , operated and thrown out of 25 action in suitable way, as by means of the fast and loose band-wheels B' B' and a driving-band, is mounted in bracket-bearings b b , secured to uprights b' b' of a suitably-constructed main frame of the machine. The 30 driving-shaft is geared with and rotates a main actuating-shaft, B^2 , by way of which the mechanism is operated, the gearing connecting the two shafts consisting of the bevel-pinion b^2 and the bevel-gear B^2 . The main actuating-shaft 35 is mounted in bearings b^3 b^4 at the ends of the main frame and in an intermediate bearing, b^5 , formed in the lower end of a slotted bracket, B^4 , which is bolted at its upper end to the under side of the top plate, C , of 40 the main frame.

Eccentrics C' C' upon the main actuating-shaft engage eccentric rings or straps C^2 C^2 , which have jointed connection by way of pivot-studs c c with a cross-head slide, C^3 , which 45 carries the vertically-reciprocating frame A^4 . These pivot-studs are fixed to or formed with the end cross-arms, c' c' , of the cross-head slide, and these arms are joined by the connecting-piece or intermediate cross-arm, c^2 , 50 of the cross-head slide, which has a downwardly-projecting slotted slide, c^3 , loosely embracing the main actuating-shaft and working in a guideway (shown as formed by grooves c^4 c^4) in two hanger-brackets, C^4 C^4 , of the main frame. These guideway-brackets are strongly 55 secured at their upper ends to the under side of the main frame-plate C , and project downwardly at opposite sides of the actuating-shaft B^2 . Four supporting-posts, D , (shown 60 as cast with the reciprocating frame A^4), are detachably secured to the cross-head slide. These posts are tubular, rest at their lower ends upon the corners of the cross-head slide, (the ends of the cross-arms c' c'), and are 65 secured in place by screw-rods d passing through them and through the ends of the arms c' c' and nuts upon the ends of these

rods. The connecting or intermediate cross-arm, c^2 , moves in the slot of the bearing-bracket B^4 , and the supporting-posts pass 70 through openings in the frame-plate C . In order to secure most accurate adjustment of the parts, two diagonally-opposite supporting-posts are provided at their lower ends with short lugs or fixed pins to engage with corresponding holes in the ends of the arms c' c' . 75 As will be understood from the above description, the reciprocating frame A^4 is raised and lowered by the rotation of the actuating-shaft. As in this instance shown, the printing is done by means of a stamp, the letters, &c., being upon the block D' , suitably cushioned and secured in the stamp-holder D^2 , carried by the reciprocating frame A^4 . It is obvious that in lieu of the block-stamp a 85 chase might be employed to provide for the use of type and for varying the form at will. The stamp-holder is adjustably attached to its reciprocating carrying-frame by being screwed to angle-bars d' , secured to the 90 frame by bolts d^2 , provided with nuts and passing through elongated slots at right angles to each other in the frame and angle-bars, respectively. A pad or block, C^5 , is secured in the holder c^5 c^5 , attached to the main frame-plate C , and supports the paper while being 95 acted upon by the stamp.

Although it may be preferable for some work to resort to the usually-employed inking pads or rollers, I in this instance use, 100 instead of them, an ink-ribbon, D^3 , which passes beneath the stamp of the printing apparatus and about rollers D^4 D^4 at opposite sides thereof, carried by the reciprocating frame A^4 . At their inner ends the ink-ribbon 105 rollers have bearing in inwardly-bent bracket-arms D^5 D^5 , secured to the opposite sides of the reciprocating frame, and at their outer ends their bearings are provided in the lower ends of spring-arms d^3 d^3 , each adjustably secured by a bolt or screw, d^4 d^4 , to the end of 110 said frame. As shoulders are formed in making the reduced ends or journals of the rollers, it will readily be understood that the pressure of the spring bearing-arms against 115 the adjacent shoulders of the rollers, and the corresponding pressure of the opposite shoulders of the rollers against their bearing-arms D^5 D^5 , produces sufficient frictional resistance to the turning of the rollers to prevent their 120 accidental movement, and thus the ink-ribbon is kept under proper tension. The ink-ribbon is automatically fed from one roller to the other by means of ratchet-wheels d^5 d^5 and a 125 spring-pawl, D^6 . Each of the ink-ribbon rollers has one of the ratchets fastened to it near its inner end, and the ratchet-actuating pawl is removably attached by the bent lower end of its spring-shank d^6 to the top plate, C , of the main frame and projects upwardly, terminating at top in the nose or hook for engaging the ratchet in connection with which it operates. The pawl is shown as resting 130 upon a block, d^7 , on the main frame top plate

and secured by a bolt, d^8 , passing through its bent shank and through the block into a threaded hole of the top plate. There are two of these holes, d^9 , in the top plate, (the unused hole is shown in Fig. 3,) so that the pawl may be adjusted to actuate either roller to feed the ink-ribbon first one way and then the other, winding it upon the opposite rollers alternately.

From the above description it will be seen that upon the upstroke of the reciprocating frame carrying the printing apparatus the pawl will actuate a ratchet to turn the ink-ribbon rollers and feed the ribbon, while yielding to prevent interference with the parts upon the return-stroke, and that when the ribbon has been unwound from one roller and wound upon the other the pawl is shifted so as to feed the ribbon in the opposite direction.

Fig. 12 represents a modification of the printing apparatus, whereby provision is made for chromographic printing or for lettering in different colors, if desired, two stamps and two ink-ribbons being provided, (more may be provided,) one stamp acting upon a length of the paper strip to be subsequently formed into a box-tube blank simultaneously with, but upon, a portion a step in advance of that being acted upon by the other stamp, as will readily be understood, the stamps being so constructed that the printing done by one does not interfere with that done by the other. For instance, one stamp might print in lines on one side of the center of the strip, and the other in lines on the opposite side of the center, or the printing be in alternate parallel lines by the respective stamps.

Vertically-reciprocating combined cutters and creasers or scorers carried by the reciprocating frame A^4 are as follows: The single head or holding frame E for all the cutters and creasers is of rectangular form and provided with the opposite side flanges, $E' E'$, slotted to receive securing-bolts, which, by engaging with cross-slots in the reciprocating carrying-frame A^4 , adjustably secure the head to the underside of said frame against a suitable cushion-block, e , in obvious way. The cutters and the creasing-plates, with clamping and spacing blocks, are clamped in place by two sets of clamping-screws, e' and e^2 , passing through screw-taps in two adjacent sides, $E^2 E^3$, of the head, the screws of the one set extending at right angles with those of the other. For rectangular boxes with folding ends and securing-flaps (see Figs. 23 and 24) there are provided four longitudinal creasers, $E^4 E^5 E^6 E^7$, for predetermining the side corners of a box by the longitudinal creases e^3 $e^4 e^5 e^6$ of the strip, and correspond in length with the length of a box when it has its ends folded and closed by the securing-flaps.

In line with and abutting against the ends of the creasers most remote from the strip-supplying roll there are four longitudinal cutters, E^8 . For transversely creasing and transversely and diagonally cutting the strip there

are provided creasers and cutters which together operate upon a portion of the length of each box tube-blank equaling the length of the cut made by each longitudinal cutter E^8 . The transverse creaser F , which is next the strip-supplying roll, creases the strip at f for a portion of its width corresponding with that included between the extreme longitudinal creases $e^3 e^6$. The transverse cutter G cuts at g in line with the crease f from a point in line with the longitudinal crease e^3 to the adjacent margin of the strip. The pair of diagonal cutters G' , make the short cuts $g' g'$, extending, respectively, from the margin to the cut g and from this cut to a point in line with the crease e^3 . The transverse cutter G^2 is in line with the creaser F , and cuts at g^2 from a point in line with the longitudinal crease e^6 to the adjacent margin. The above-described transverse creasers and cutters extend in a line parallel with the two lines of transverse cutters and creasers now to be described. The creasers F' and F^2 respectively form the creases f' and f^2 , the crease f' extending from the margin to a point in line with the adjacent longitudinal crease e^3 , and the crease f^2 extending between points in line with the longitudinal creases $e^4 e^5$. The cutter G^3 makes the cut g^3 in that part of the strip which would cross between the longitudinal creases $e^3 e^4$ were they extended, and the cutter G^4 makes the cut g^4 , reaching from a point in line with the longitudinal crease e^5 to the margin next the longitudinal crease e^6 . The creasers $F^3 F^4 F^5$ of the remaining line respectively form the transverse creases $f^3 f^4 f^5$, the crease f^3 extending from the longitudinal crease e^4 to the margin adjacent to the crease e^3 , the crease f^4 extending from near the longitudinal crease e^4 to near the longitudinal crease e^5 , and the crease f^5 extending between the longitudinal creases $e^5 e^6$. Two short transverse cutters, G^5 , make the cuts g^5 , extending to the opposite ends of the transverse crease f^4 from the longitudinal creases $e^4 e^5$, and the transverse cutter G^6 makes the cut g^6 from the longitudinal crease e^6 to the adjacent margin. The pair of diagonal cutters G^7 make the two short cuts $g^7 g'$, extending from the opposite ends of the transverse crease f^4 to points in line with the longitudinal creases $e^4 e^5$, respectively.

A suitably-slotted stationary plate, H , (best shown in Figs. 3 and 8,) for co-operating with cutters and creasers in obvious way, is supported beneath the cutter and creaser head upon a die-block, H' , to which it is bolted. This die-block is secured in a holder attached to the top plate of the main frame and has grooves corresponding with the slots of the plate H . The holder consists of angle-bars $H^2 H^3$, to and between which the block is screwed, the block resting on the top plate of the main frame and the angle-bars being adjustably secured in place by means of bolts passing through slots in them and in the top plate. A passage-way, H^4 , is provided be-

neath the plate II for the paper strip between the bars or ribs h h , secured to or formed with the supporting-block II'.

In order to provide room for properly securing the printing apparatus and the cutters and creasers and for actuating these parts of the mechanism without interfering with each other, the cutters and creasers are located a distance in advance of the printing apparatus equaling the length of feed of the strip at one actuation, or so that during operation there shall be between the printing apparatus and the cutters and creasers a portion of the strip of a length such as is advanced at each feeding-actuation.

The operation of the mechanism so far as described will be seen to be as next explained, it being understood that there is provided proper feeding mechanism, by which the strip is fed intermittently, so as to advance it at each actuation a distance corresponding to the length of the longitudinal creases, together with the length of the longitudinal cutters, which distance is the same as the length of the longitudinal creases, adding the length of that portion of the strip which is included between the transverse crease f and the line of creases f^3 f^4 f^5 , and also the same as the length of a box-tube blank less the combined length of the two securing-flaps f^6 f^6 , formed at opposite ends of the blank between the cut g and crease f' and between the creases f^2 and f^4 . With the mechanism properly timed, and assuming that the strip of paper has been properly adjusted and the machine set in motion after the first feeding action, the printing for the leading box-tube blank takes place, the cutting and creasing occurring at this time being in a portion of the strip which is not printed. After the second feed the printing for a second blank is done, and the advance end of the first-printed blank is acted upon by the transverse creasers and cutters and the diagonal cutters, the longitudinal cuts and creases being made in the unprinted portion of the strip. After the third feed a third blank is printed. The advance end of the second blank and the rear end of the first blank are acted upon by the transverse and diagonal cutters and the transverse creasers. The action of the longitudinal creasers is upon the first blank between the folding front and rear ends of the box to be made, and the longitudinal cutters act upon the front end of the first blank. After each subsequent feed there is produced a cut and creased box-tube blank, and each of these blanks is united with the next by the connecting-neck or narrow unsevered creased portion f^4 . This neck, while serving to make a sufficiently strong connection between the blanks about midway the width of the strip, to provide for feeding the strip by a pull or draw, may be torn or cut in the line of the short crease f^4 to separate the blanks when they are to be used for boxes. When, instead of making the boxes with folding ends

and securing-flaps, they are to be made with open ends (see Figs. 25 and 26) to serve as the cases of drawer-boxes, such as used for containing matches, &c., the cutters and creases are modified, as shown in Figs. 21 and 22. In accordance with this modification the longitudinal and diagonal cutters are dispensed with, and instead of the before-described transverse cutters and creasers, I employ the single short transverse creaser, i , between the two transverse cutters I I, which cut from this creaser to the opposite margins of the strip, leaving the creased narrow connecting portions or uniting-necks between the adjacent blanks. One transverse clamping-block, I', is used instead of the three transverse clamping and spacing blocks before employed. The longitudinal clamping and spacing blocks are made longer than before, the longitudinal creasers are made longer than before, (the increase in the length of these creasers equaling the length of the discarded longitudinal cutters,) and the stationary plate II and die H' for the cutters and creasers are modified in obvious way. No other alterations are needed to make the boxes in accordance with this modification.

Although I deem it best to crease the strip, as at f^4 , across the narrow connecting-neck between one blank and another, this creasing is not absolutely necessary and may be dispensed with if not desirable under any circumstances.

After the strip is cut and creased the box-tube blanks are each pasted at or near one edge by mechanism as follows: A paster, consisting of a rotating brush, J, formed by a wheel with radial bristles at its periphery, is secured upon the inner end of a shaft, J', mounted to rotate in bearings j j in a rocking bracket, J², of angular form. The bearings for the shaft of the paster are formed in forks of the paster-bracket, and this bracket is mounted by bearings j' j' to rock vertically about a supporting-stud, j^2 , extending at a right angle with the shaft of the rotating paster. This supporting-stud is fixed to a bracket, J³, upon the top plate of the main frame. A downwardly and inwardly projecting bent actuating-arm, J⁴, suitably secured, as by screws j^3 j^3 at its outer and upper end to the rocking paster-bracket, is provided at its opposite or inner end with a pin, j^4 , bearing upon the periphery of a controlling-cam. (Shown as formed in two sections, J⁵ J⁶.) The actuating-arm J⁴ of the paster-bracket is held down to its controlling-cam by gravity; but if deemed essential a spring may obviously be provided to bear down upon the arm to render its action more certain. The main section J⁵ of the controlling-cam is fast on the main actuating-shaft B², and the other section, J⁶, is adjustably secured to the main section, in order that the cam may be adapted to lift the paster-bracket and allow it to drop at proper times. The adjustable section is secured to the main section by means of a set-

screw, j^5 , passing through a curved slot, j^6 , in the main section and engaging a screw-tap in the adjustable section. It will be seen that when the recessed portion of the controlling-cam is presented to the pin of the paster-actuating arm the paster-bracket descends, the paster at this time being brought in contact with the strip, and that when the regularly-curved portion of the cam is acting on the pin 5 the paster-bracket is elevated, at which time the paster is lifted above the strip. The paster-shaft J' is rotated by a crossed belt, j^7 , (shown dotted in place,) passing about the small pulley J' , fast on the paster-shaft, and about a 10 larger driving-pulley, J^8 , fast on a short driving-shaft, J^9 , rotated from the main actuating shaft by bevel-gears j^8 , j^9 . The paster driving-shaft J^9 is mounted in bearings in the ends of the forks or arms of a hanger-bracket, K , which 15 is secured by screws to the under side of the top plate of the main frame. A small driving-pulley, K' , on the paster driving-shaft imparts motion by way of a crossed belt, K^2 , to a larger pulley, K^3 , fast on the outer end of a 20 shaft, K^4 , rotating in bearings k , k in the arms of a bracket, K^5 , secured by screws upon the top plate of the main frame. At the inner end of this shaft K^4 there is secured a paster-supplying wheel, k' , partly submerged in paste 25 in a reservoir, k^2 , supported over that edge of the strip to be pasted by a yoke-like bracket, k^3 , secured at its opposite ends to the top plate of the main frame. When at work or in contact with the edge of the strip to be pasted, 30 the paster rotates clear of its paster-supplying wheel; but when the paster is elevated, as before explained, its bristles rotate in contact with the supply-wheel, which rotates constantly in the paste in the reservoir, but much 35 slower than the paster. In this way the paster is supplied with paste from the paste-reservoir at each intermission in the feed of the strip and descends upon the edge of the strip and applies paste to it every time it is advanced. 40 A line of paste is applied to each box-tube blank upon that edge next the longitudinal crease e^6 of a length corresponding with that of said crease and equaling the length of the pasted fold to be made. By rendering the 45 controlling-cam of the paster adjustable, as before explained, provision is made for varying the length of the lines of paste applied to the strip, and so box-tubes for either of the forms of boxes represented may be properly 50 pasted to thoroughly unite their seams. The strip while having paste applied to one edge of the box-tube blanks passes over and is supported by a plate, L , that portion of the strip to which the plate is applied by contact of 55 the paster passing over the narrow and round-edged side lug, l , of the supporting-plate. By providing this lug and causing the edge of the paper to be pasted to pass over it and overhang the edge of the supporting-plate a 60 more thorough application of paste is insured, as the paster slightly depresses the edge of the strip at either side of the lug, and the 65

bristles thus act upon the strip not only above the lug, but at either side thereof, or somewhat below the level of its top surface. In this way 70 it will be seen that a longer portion of the strip is being acted upon at the same time than could be were the lug dispensed with, and the descent of the ends of the bristles below the level of the top of the plate to follow the slight curvature of the strip at the sides of the lug prevented. The connected and pasted box-tube blanks are successively folded about a thin blade-like former, L' , as 75 they are in turn presented to it by the intermittent advance of the strip. The former is shown as formed by a narrowed extension of one side of the plate L of somewhat less than half the width of this plate. The former is beveled at its edges, and is of a width corresponding, or nearly so, with the width of the pasted flattened box-tube to be formed, and with the combined width of one of the wide sides (the top or bottom) and one of the narrow sides of the box to be produced. 80

When a pasted box-tube blank is brought over and comes to rest upon the former, it is acted upon by two pairs of folders and the blank is folded into a flattened tube along the lines of the creases e^3 , e^5 . Two vertically- 85 reciprocating primary folders, M , M , of similar construction, are carried by the reciprocating frame A^4 , to and beneath which they are adjustably secured, in suitable way, as by set-screws passing through slots in the reciprocating frame and engaging screw-taps in the flanged upper ends, l' , of the folder-shanks. Each of these folders is made with two slots, 90 m , producing the three short folding arms or lugs m' , and the folders are secured to their reciprocating carrying-frame in such manner that the distance between the folding-lugs of the respective folders very slightly exceeds the width of the former, in order that the folding-lugs may work close to the opposite edges 95 of the former while embracing the blank between them and the former edges. Upon the downward movement of their carrying-frame the folders come in contact with the blank between its opposite margins and the creases e^3 , e^5 , and give to the blank an inverted-trough 100 form, as will be understood. The two folders 105 N , N' , which act upon the downwardly-turned sides of the blank to fold them inward and upward to the former, with the pasted edge 110 above or inside of and lapped by the side of the blank next the longitudinal crease e^3 , are 115 similar in construction and operate alike, with the exception that the folder N , which turns in the pasted edge, acts in advance of the folder N' , so that the unpasted edge will be 120 outside. Each of these side-folders consists of a plate having the slot n and the two short spring-arms or yielding folding-lugs n' , n' , 125 curved downwardly at their outer ends, 130 formed at the sides of the slot. These plates are carried by supports N^2 , N^2 at the upper ends of vibrating levers N^3 , N^3 , with spaces (see Fig. 7) between the folding-plates and the sup-

ports to provide for the slight yielding of the plates. Each of the folders is rendered adjustable, being for this purpose provided with slots n^2 n^2 , by means of which and set-screws passing through them and through a clamp-bar, n^3 , and engaging screw-taps in the supports, the folders are held in their adjusted position.

Each folder-lever N^3 is provided at its lower end with a pivoting-sleeve or long hub, N^4 , by which it is mounted upon a stud, N^5 , fixed at one end to a downwardly-projecting bracket, N^6 , secured to the under side of the top plate of the main frame, and the levers work through a slot in this plate. The levers are of elbow form, each being provided with the short arm N^7 at its lower end, having a pin, n^4 , carrying a roller, n^5 , acted upon by a controlling-cam, N^8 , on the main actuating-shaft. The pivoting-sleeve of each lever has a spring, n^6 , coiled about it, one end of the spring bearing against the under side of the frame top plate, and the other against a pin, n^7 , of the short arm of the lever. These springs act to keep the rollers n^5 in contact with the controlling-cam and to move the folders inward and cause them to act with a yielding pressure upon the blank. The shape of this controlling-cam is such (see Fig. 7) that the folder N is acted upon in advance of the action of the folder N' , so that the folder N is moved both inward and outward slightly before the corresponding movements are imparted to the folder N' , both folders acting for a time together upon the blank with a yielding upward pressure, the cam being cut away sufficiently for that portion of its periphery which comes beneath the rollers n^5 during the action of the folders upon the blank to allow the springs n^6 to act freely, the rollers at times being out of contact with the cut-away portion of the cam, as will readily be understood. The lugs n' of the folders N N' pass to the blank by way of the slots m of the vertically-reciprocating folders.

To keep the paper down upon the former a presser is provided above the former and the blanks are fed between this presser and the former. As shown, the presser consists of a plate, O , acting in turn upon the blanks between it and the former, provided with a shank, o , by which it is guided, and allowed to play vertically to the needed extent in a guideway-opening in an overhanging arm, O' , secured to the bracket k^2 . The presser acts by gravity, and its shank has a pin, o' , attached to it and projecting out at a slot in the end of the arm O' to provide for raising the presser to adjust the strip.

The primary folders M M , after acting upon a blank, are elevated to clear it before its advance; but the final folders N N' continue to act upon the blank during the time, or the greater portion of the time, of its advance by feeding mechanism, such as next to be described, this continued action of the final folders serving to render more certain the proper adhesion of the pasted seam.

The top plate of the main frame is provided with a guideway, P P , for a reciprocating carrier for the feeding-clamp. The carrier consists of the slide P' , beveled at its edges to work in the guideway, and having the side arms, P^2 P^2 , each perforated at its outer end. The slide also has a perforated lug, p , and two parallel ribs, $p' p'$. A bent clamp-lever, P^3 , of U shape, is pivoted between the arms P^2 P^2 by its sleeve or hub p^3 and the pin p^3 passing through the sleeve and through the perforations in the outer ends of the arms. A clamp-head, P^4 , having attached to its under face one or more pieces of rubber or equivalent, is shown as formed with the upper end of the clamp-lever and as connected with one end of a coiled spring, P^5 , the other end of this spring being connected with the slide-lug p . This spring acts with a tendency to move the clamp-head downward against or toward the ribs $p' p'$, between which and the clamp-head the strip of box-tubes is clamped at the proper time. A guide, P^4 , formed by a curved strip of metal screwed to the clamp-head, serves to direct the strip beneath the clamp-head. A smooth-surfaced arm, P^6 , curved downwardly at its outer end and firmly secured to the frame top plate by screws passing through its flange p^5 , is curved downward upon the upper surface at its inner end, where it terminates close to the former, so that the connected flattened tubes pass to and over it. This tube-supporting arm projects over the slide P' and between the clamp-ribs $p' p'$ thereof. The clamp-lever P^3 , which passes through and is reciprocated in a slot in the frame top plate, is provided at its lower end with a cam-actuated elongated pin, p^6 , and a stud, p^7 , secured to the slide P' and projecting downwardly through a slot of the frame top plate, carries a roller, P^7 , which is acted upon by a cam to move the reciprocating carrier of the feeding-clamp in one direction or away from the former. This carrier is moved in the opposite direction or toward the former by a spring, Q , coiled about midway its length and connected at its opposite ends to the frame top plate and to the slide. This spring acts constantly with a tendency to move the carrier inward or toward the former and folders. The cams R R' for actuating the feeding mechanism are shown as formed together, and they are secured to the main actuating-shaft. The cam R , which acts by its periphery upon the pin p^6 of the clamp-lever, is at one end of a short cylinder, which at its other end is cut away to form the cam R' for acting upon the roller of the stud p^7 of the clamp-carrier slide.

By reference to Fig. 6 it will be seen that for somewhat more than one-third of each revolution of the cam R the pin p^6 is acted upon by that portion r of the cam which is of regular curvature and of greatest radius, and that while the regularly-curved portion r' of the cam which is of least radius and extends for somewhat more than half-way around it is pre-

sented beneath the pin, the spring P^5 is allowed to act to depress the clamp-head with sufficient force to clamp the strip of box-tubes and insure their movement with the clamp unless there is some unusual obstruction to the feed. As the clamp-carrier reciprocates, the crank P^6 slides crosswise of the cams' peripheries. While the incline r^2 of the cam R' is acting on the roller P^7 the clamp-carrier is advanced or moved outward, the clamp being down upon the strip. When the straight or regular portion r^3 is presented to the roller, the carrier comes to rest, and during this pause in its movement the clamp is elevated to release the strip of tubes. When the incline r^4 is opposite the roller, the spring Q acts to move the carrier inward to the extent allowed by an adjustable stop, shown as formed by a screw, q , working in a fixed lug, q' , at one side of the inner end of the guideway for the carrier-slide, and against which the inner side arm, P^2 , of the carrier abuts at the completion of its inner stroke. When, upon the completion of the inner stroke of the carrier, the cut-away portion r^5 of the cam is brought opposite the roller P^7 , and there is a slight pause in the movement of the carrier, the clamp-head is brought down preparatory to the advance of the clamp-carrier. The length of feed may be varied by adjustment of the stop q , the cam R' being cut away at r^5 to an extent sufficient to allow of greater movement being imparted to the carrier by its spring than is allowed to be given to it when the stop is adjusted, as in this instance shown. The strip of connected box-tubes passes over the tube-supporting arm P^6 to a hinged inclined conductor, S , by way of which they are directed to a roll, T , about which they are formed into a compact circular bundle or roll. The roll T automatically keeps the strip under tension and tightly winds up the box-tubes, insuring that the strip shall be kept taut during intermissions in the feed, before reaching the feed-clamp, and always keeping taut the length of flattened connected tubes between it and the clamp-head, while compressing the tubes wound about the roll and thus insuring that the pasted seams shall be held under pressure until the paste is completely dry. The tube-conductor S is hinged at its upper end to the frame top plate close to the outer end of the tube-supporting arm P^6 , so that the strip of tubes passes from this arm directly onto the conductor. The hinge for connecting the conductor to the frame top plate is shown as formed by a bent rod, s , secured at one end by a screw, s' , to the plate, and forming by its horizontally-extended opposite end a pivotal support for the conductor to allow of its vertical play to conform to the size of the roll of paper upon which its lower end rests, as will readily be understood. The roll T , about which the tubes are automatically wound, is mounted by its sleeve or long hub T' upon a stud, t , supported at one end by the frame-bracket U . The roll is provided

with a ratchet, u , and a spring-actuated pawl, u' , and at one end the sleeve-hub of the roll forms a drum, about which is wound a cord, v . The cord is attached at one end to the drum portion of the hub about which it is wound, and passes over a pulley, v' , at the top of a high standard, W , and has a weight, w , secured to its opposite end. This standard is secured at its base to the frame bed-plate. It will readily be seen that by the action of the weighted cord and pawl and ratchet the tubes are wound tightly about their roll.

From the above description it will be understood that starting with a strip of paper or its equivalent, of proper width, I by my method manufacture in rolls series of connected flattened longitudinally seamed and pasted box-tubes, which may be stored in small space or compactly packed for transportation and separated as required for use. The tubes may either be separated and made ready for use in advance, or rolls of tubes for boxes—such as shown by Fig. 24—may be hung upon reels and the tubes separated as required for use by grocers, confectioners, and others. It will further be seen that by slight modifications—such as varying the cutters and creasers—tubes for boxes of other form than those shown may be manufactured without departure from the spirit of my invention, and also that the tubes may have their connecting-necks formed with lines of small perforations in place of the mere creases F^4 to facilitate the separation of tubes by tearing them apart, a creaser serrated or provided with a row of pointed pins being used instead of the straight-edged creaser F^4 described.

I claim as of my own invention—

1. As an improvement in the art of manufacturing boxes from a strip of paper, &c., the described method of preparing the connected blanks for pasting and folding, consisting in intermittently advancing the strip, and during intermissions in its advance movement cutting and creasing to successively and completely form the respective blanks of a series of unfolded unpasted blanks connected at their ends by narrow necks, substantially as set forth.

2. As an improvement in the art of manufacturing boxes from a strip of paper, &c., the described method of preparing the connected printed blanks for pasting and folding, consisting in intermittently advancing the strip, successively printing the respective blanks during intermissions in the advance movement of the strip, and cutting and creasing other blanks, also during intermissions in the advance movement of the strip, to successively complete the respective blanks of a series of unfolded unpasted blanks connected at their ends by narrow necks, substantially as set forth.

3. As an improvement in the art of manufacturing boxes from a strip of paper, &c., the described method of producing the connected box-tubes, consisting in intermittently ad-

vancing the strip, during intermissions in its advance movement cutting and creasing it to successively completely form the respective unfolded unpasted blanks of a series, with 5 the narrow necks connecting them at their ends, applying paste to the successive blanks, and during intermissions in the advance movement of the strip folding previously cut and creased pasted blanks into flattened connected box-tubes, substantially as set forth.

15 4. As an improvement in the art of manufacturing boxes from a strip of paper, &c., the described method of producing and compactly bundling and compressing the connected box-tubes, consisting in intermittently advancing the connected cut and creased blanks, applying paste, folding into flattened connected box-tubes, and winding them under tension 20 into a compact roll, substantially as set forth.

25 5. As an improvement in the art of manufacturing boxes from a strip of paper, &c., the described method of preparing the connected blanks and producing and compactly bundling and compressing the connected box-tubes, consisting in intermittently advancing the strip, cutting and creasing it to successively form the respective blanks of a series, with the narrow necks connecting them, applying 30 paste to the blanks, folding the blanks, and finally winding them into a compact roll, substantially as set forth.

6. As a new article of manufacture, the series of connected pasted flattened box-tubes, substantially as and for the purpose set forth.

7. A compact roll of connected pasted flat- 35 tened box-tubes, substantially as and for the purpose set forth.

8. The combination of the paper-supplying roll, the vertically-reciprocating cutters and creasers, their head, the reciprocating frame 40 by which the head is carried, pasting apparatus, substantially such as described, the primary folders carried by said reciprocating frame, the final folders, the springs acting upon them, feeding mechanism, substantially 45 such as described, the spring by which it is moved one way, the main actuating-shaft, by mechanism substantially such as described, connected with which the reciprocating frame and the final folders are actuated and the 50 feeding mechanism moved in opposition to its spring, and the bundling-roll automatically actuated to wind up the connected box-tubes, substantially as and for the purpose set forth.

9. The combination of the former, the vertically-reciprocating primary folders slotted and provided with the folding-lugs, and the final folders provided with the folding-lugs to enter the slots between the lugs of the primary folders, substantially as and for the purpose 55 set forth.

In testimony whereof I have hereunto subscribed by name.

McCLINTOCK YOUNG.
